Monica Blvd., Santa Monica, Calif. 90404

Filed Aug. 9, 1965, Ser. No. 478,317
7 Claims. (Cl. 222—146)

This invention relates generally to methods of and apparatus for dispensing a shaving lather in heated and moistened condition. More particularly, this invention provides an aerosol-type container with an attached apparatus which causes the lather therein to be heated and moistened by direct contact with hot water.

It is well known that shaving is made easier and more comfortable when a heated lather or cream is used. In this regard, a number of devices have been proposed which cause the lather or cream contained within a pressurized aerosol container to be heated.

Among these are devices equipped with electrically powered heating elements for heating the lather as it is being dispensed. These devices usually require an external source of electrical energy and thus are limited in portability. Furthermore, many are complex in construction and thus expensive to manufacture and repair.

Other devices have been proposed which utilize heat exchange units such as coils of copper through which the lather is propelled and heated by warm water surrounding or passed over the coils. These devices eliminate the hazards of electric heaters but are often ineffective because the discharge rate of the lather is too fast to allow time enough for the lather to absorb heat from the surrounding heating medium. Thus, the lather is not raised to temperatures substantially higher than room temperature or close to the temperature of hot tap water.

In addition to the desirability of hot lather, it is important that the lather contain sufficient moisture to soften the beard and allow easy shaving. In this regard shaving lather dispensing devices in present use do not provide means for moistening the lather as it is dispensed.

With the foregoing in mind, it is accordingly a primary object of the present invention to provide a novel aerosol type device which avoids the foregoing problems and yet dispenses shaving lather in a heated and moistened condition.

More particularly, it is an object to provide a novel dispensing device which provides heated lather without requiring external energy sources or complicated coil structures, to the end that a more efficient and less costly and complex product is provided.

Another object is to provide a novel lather heating device which may be attached to a conventional aerosol type container with only minor modifications being required, so that a preferred brand of lather may be used and heated in accordance with the invention.

A more general object is to provide a novel method for heating and moistening shaving lather.

Briefly, these and many other objects and advantages of this invention are attained by providing a conventional aerosol type container with a novel dispensing device enabling the shaving lather to be provided in a heated and moistened condition by direct contact with hot water. More particularly, and in accordance with the method and preferred apparatus, the aerosol type container is provided with an outlet manifold attached to the outlet spout thereof. This outlet manifold preferably consists of an open-ended curved tube which is attached at its mid-point to a spout connected with the outlet of the aerosol container. The tube may be curved so as to overlie a portion of the top of the container to any extent desired.

2

A cylinder incorporating a screen or similar baffle means is attached or integrally formed with the top of the aerosol container. This cylinder is adapted to receive hot water directly from a tap such that the shaving lather is dispensed directly into the hot water within the cylinder. A removable top for the cylinder may be provided if desired.

The screen is disposed above the outlet manifold and serves to disperse the lather as it flows upwardly to the surface of the water, thus exposing greater portions of the lather to the heat of the surrounding water. The user then simply removes the top and scoops the lather out of the cylinder and applies it to his face.

An alternative means for removing the lather may be provided by substituting for the top a cover incorporating a perforated cup member. When the cover is positioned over the cylinder, the lather in the cylinder adheres to the cup and may thus be removed with the cover.

A better understanding of the invention will be had by now referring to the accompanying drawings, in which:

FIGURE 1 is an exploded perspective view partly broken away of an aerosol type container and dispensing device in accordance with the invention;

FIGURE 2 is a fragmentary cross-sectional view of the device in assembled relationship;

FIGURE 3 is an exploded perspective view partly broken away, showing a novel cover structure for the device; and,

FIGURE 4 shows the members of FIGURE 3 in assembled relationship.

Referring first to FIGURE 1, there is shown a conventional pressurized aerosol type container 10 having attached thereto a conventional valve-operating push button 11. Attached to the top of the container 10 is a downturned outlet spout 12, made for example of plastic, to which is attached an open-ended curved tube 13. The spout 12 and tube 13 together form an outlet manifold for the container 10. It is to be understood that the length of the tube 13 may be varied to any extent desired.

Positioned above the container 10 is a cylinder 14 which has the lower end thereof terminating in a flanged rim 15 which is adapted to be secured by adhesive or the like to the top of the container 10 so as to be axially aligned therewith. Secured within the cylinder 14 is a circular screen 16 having a central opening 17 including a cutout notch portion 18. The screen 16 also includes a series of circumferentially spaced ports 19. The notch portion 18 is adapted to accommodate a portion of the spout 12 when the screen and cylinder are assembled on top of the container 10.

A removable top 20 is adapted to cover the upper end of the cylinder 14.

Referring now to FIGURE 2, it will be seen that the cylinder 14 forms a chamber in conjunction with the top of the container 10. The diameter of the central opening 17 of the screen 16 is greater than the diameter of the push button 11 so that the screen 16 may be positioned adjacent a raised central portion of the top of the container 10, with the notch 18 (FIGURE 1) fitting over a portion of the spout 12. The tube 13 is thus disposed below the screen 16.

In operation, the cylinder 14 is partially filled with hot water from a hot water tap. The push button 11 is then depressed downwardly as shown by arrow A and shaving lather is emitted from the container 10, through the spout 12, and out through the ends of the curved tube 13. The lather L flows upwardly through the ports 19 which disperse the lather and cause it to be partially mixed with the hot water within the cylinder 14. As the lather floats to the surface of the hot water it absorbs heat and moisture directly therefrom. This heating of the lather may be rendered more efficient by positioning the re-

movable top 20 over the cylinder for a short period of time to hold in the heat. The user then simply removes the top 20 and scoops the lather from the surface of the water and applies it to his face.

Referring now to FIGURES 3 and 4, there is shown a substitute for the top 20 in FIGURES 1 and 2 in the form of a cylindrical cover 22 within which is positioned a circular cup member 23. The cup 23 is held by a rod 4 attached to the underside of the top portion 22a of the cover 22 at the center thereof and extending downwardly to a point at which it is connected to the center of the cup member 23 as shown. The cup 23 itself includes a series of circumferentially spaced openings 25 in its top surface.

The outer periphery of the cup wall is spaced from the outer periphery of the cover wall a distance D as shown. This distance is designed to be at least as great as the thickness of the wall of the cylinder 14, such that when the cover is placed over the top of the cylinder, as best shown in FIGURE 4, the cup 23 will fit therein.

In the operation of the embodiment of FIGURES 3 and 4, the hot water and lather are introduced into the cylinder 14 in the manner as above-described with reference to FIGURE 2.

The cover 22 is then placed over the top of the cylinder 14 and moved downwardly thereon, thus moving the cup 23 into contact with the lather L in the cylinder.

In so doing, air within the cylinder is allowed to escape upwardly into the cover 22 through the openings 25 defined within the cup 23 and as indicated by the arrows in FIGURE 4.

The lather L adheres to the underside of the cup, such that when the cover and cup are removed from the cylinder, the user can simply scoop the lather from the cup and apply it to his face. The cover thus serves the dual function of first: holding the heat of the water in the cylinder while the user is preparing his shaving equipment, and second: providing an easy means for removing the heated and moistened lather for use.

From the foregoing description, it is apparent that the present invention provides a method and means for heating and moistening shaving lather by direct contact with hot water thereby eliminating the need for electric heaters and heat exchange units in the form of coils and the like. Moreover, because of the direct contact of the lather with hot water, a greater heat transfer efficiency is provided since no intervening medium is employed. The shaving lather is thus dispensed in a condition which permits easy and comfortable shaving and by a device which is simple in construction and does not require external energy sources.

Various changes falling within the scope and spirit of this invention will occur to those skilled in the art. The shaving lather dispensing method and structure is, therefore, not to be thought of as limited to the specific examples set forth.

What is claimed is:

1. Means for providing a heated, moistened lather from an aerosol-type container, comprising: an outlet manifold connected to said container and communicating with a cylinder containing hot water; and lather dispersing means positioned within said cylinder whereby lather emitted from said manifold and through said dispersing means is heated and moistened by direct contact with said water

in said cylinder, a cover adapted to be fitted over the top of said cylinder; and a cup positioned within said cover whereby when said cover is fitted over said cylinder, lather in said cylinder will adhere to said cup so as to be removable therewith.

5 2. Means for providing a heated, moistened lather from an aerosol-type container according to claim 1, in which said dispersing means includes a circular screen positioned above said manifold and having a series of ports extending therethrough.

10 3. Means for providing a heated, moistened lather from an aerosol-type container, comprising: an outlet manifold connected to said container and communicating with a cylinder containing hot water; and lather dispersing means positioned within said cylinder whereby lather emitted from said manifold and through said dispersing means is heated and moistened by direct contact with said water in

15 said cylinder, said outlet manifold comprising a radially outwardly extending spout and a curved, open-ended tube beneath said dispersing means attached midway between the ends thereof to said spout.

20 4. Means for providing a heated, moistened lather from an aerosol-type container having a dispensing spout including a radially outwardly and axially downwardly extending portion comprising: an open-ended curved tube attached to an end of said spout forming a flow passage therewith; a cylinder having its lower end terminating in a flanged rim overlying the top of said container so that said cylinder is axially aligned therewith; a circular screen

25 positioned within said cylinder, said screen having a central opening including a cutout notch portion, said screen further having a series of circumferentially spaced ports, said screen being positioned adjacent to the top of said container with said notch portion accommodating said

30 portion of said spout so that said tube lies between a portion of the top of said container and said screen whereby said cylinder may be filled with hot water so that when lather is dispensed through said spout and tube, it will flow upwardly through said ports and be partially mixed

35 with hot water contained within said cylinder.

40 5. The subject matter of claim 4, including a top adapted to be positioned on said cylinder to hold heat therein.

45 6. A dispensing means according to claim 4, including a cover incorporating a cup member; said cup member having the outer periphery thereof spaced from said cover, whereby when said cover is positioned over said cylinder, said cup member will be positioned within said cylinder to receive lather and enable removal of said lather.

50 7. The subject matter of claim 6, wherein said cup includes openings to permit air to pass to the upper part of said cover as it is moved downwardly over said cylinder.
